UNITED STATES PATENT OFFICE.

THOMAS MCWATTERS, OF SWISSVALE, PENNSYLVANIA, ASSIGNOR OF TWO-THIRDS TO JOSEPH M. FLANNERY, OF BRADDOCK, PENNSYLVANIA, AND ANDREW H. MCKIM AND ALEXANDER MCKIM, SR., OF SWISSVALE, PENNSYLVANIA.

SIGNAL-LAMP.

SPECIFICATION forming part of Letters Patent No. 705,280, dated July 22, 1902.

Application filed July 24, 1901. Serial No. 69,539. (No model.)

To all whom it may concern:

Be it known that I, THOMAS MCWATTERS, a subject of the King of Great Britain and Ireland, residing at Swissvale, in the county of Allegheny and State of Pennsylvania, have invented a certain new and useful Improvement in Signal-Lamps, of which the following is a specification, reference being had to the accompanying drawings, which form a part 10 of this specification, in which—

Figure 1 indicates an elevation, partly in section, of my improved signal-lamp. Fig. 2 is a sectional elevation of the inner cylinder. Fig. 3 is a section taken on line 3-3 of Fig. 1.

15 My invention relates to improvements in signal-lamps; and the object of my invention is to produce a lamp of this character in which the greatest possible simplicity of construction and efficiency is attained.

20 To accomplish these objects, my invention consists in the novel construction and arrangement of parts hereinafter more specifically described, reference being had to the accompanying drawings, forming part hereof, 25 in which like reference characters indicate like parts wherever they occur.

Referring to said drawings, 1 is a cylindrical vessel open at the top and provided with a handle 2 and opposite thereto an opening circular in conformation and to which is connected the diverging funnel 3, the opening therein being closed by a lens or glass plate 4.

30 5 is a lamp suitably secured in the bottom of said cylinder, to the rear of and upon which is secured the vertically-disposed reflector 6, which is located at the rear of and in alignment with the lens or glass 4, the lamp being intermediate the same.

40 7 is a cylindrical vessel open at the bottom and adapted to be seated within the first-mentioned vessel, inclosing the lamp therein. The said vessel is provided with an opening 8, coinciding in diameter with the inner diameter of the diverging funnel 3, the said cylinder having secured therein at points opposite the side openings therein a red-colored lens or glass 9 and a green-colored lens or glass 10. The said cylinder 7 is provided 45 with a handle 11 or other means to rotate the

same for the purpose hereinafter described and is also provided with an annular recess 12 near the top thereof, in which the spring-controlled trigger 13 is seated and guided, the said recess having stop notches or holes 14, adapted to receive the inner end trigger, and thus lock the inner cylinder in position and against movement at such times as the different lenses are rotated into position in front of the lamp and opposite the orifice in 55 the front of the cylinder 1. The top of said cylinder 7 is closed and is provided with an annular cap perforated in the top, through which the products of combustion from the lamp are permitted to escape. 60

65 The operation of my device is as follows, viz: The lamp being in the position shown in the drawings throws a white light or open signal, which the operator can change to green or red. By withdrawing the trigger out of 70 the notch and rotating the inner cylinder to the right the green lens is brought opposite the lamp and the orifice in cylinder 1, thus showing a green light or caution signal. By again withdrawing the trigger and reversing 75 the inner cylinder—i. e., rotating it in the opposite direction—the red lens is interposed between the lamp and the orifice in cylinder 1, thus showing a red light or danger signal.

Having described my invention, what I 80 claim, and desire to secure by Letters Patent, is—

In a signal-lamp, the combination of a cylinder closed at the bottom and provided with a lamp and having a circular aperture in the 85 front thereof, an inner cylinder, adapted to be seated in said first-mentioned cylinder, having an annular recess near the top thereof, a spring-controlled trigger adapted to be seated and guided in said recess and to lock 90 the said inner cylinder in any given position, and means to rotate said cylinder, substantially as described.

In testimony whereof I have hereunto set my signature in the presence of two subscribing 95 witnesses.

THOMAS MCWATTERS.
